UNITED STATES PATENT OFFICE

2,370,290

MEANS FOR IMPREGNATING FABRICS
WITH LIQUIDS

Rudolph Herbert Czezwitzka, Pendleton, Salford, England, assignor to Texproof Limited, Pendleton, England, a British company

Application June 18, 1943, Serial No. 491,369
In Great Britain June 19, 1942

1. Claim. (Cl. 68—19)

This invention has for its object to provide an improved machine for effecting the impregnation of fabrics with volatile liquids or solutions containing volatile liquids with a minimum loss of solvent and with a minimum of skin formation on the machine due to deposit of the liquid and evaporation of solvent therefrom.

A machine in accordance with this invention comprises a tank or vessel of a length to suit the width of the fabric being impregnated, with a roller or rollers beneath the surface of the impregnating liquid in the tank or vessel, and with squeezing rollers to remove excess of liquid from the fabric as it leaves the tank or vessel, and a lid which makes a joint with the vessel except at the parts where the fabric passes into and out of the vessel, the lid at such parts coming adjacent to surfaces of the vessel, so that the thickness of the fabric serves to seal the gap between the said parts and to prevent or minimize escape of solvent there, and the said parts serve as spreader blades on both sides of the fabric and thus insure a smooth even surface spreading.

Referring to the accompanying explanatory drawings:

Figures 1 and 2 are sectional views taken at right angles to one another showing a machine constructed in one convenient form in accordance with this invention.

The tank or vessel *a* provides an internal ledge *b* at its opposite ends on to which the lid *c* is clamped by the wing nuts *d*. There is an internal flange *e* along the opposite sides of the top of the tank and the lid *c* when clamped in place extends into and below the space between such flanges, being approximately a fit between the flanges. By reason of the lid coming below the flanges, a narrow gap is left between the lower edge of the flange and the upper edge of the lid at its opposite sides, and the fabric *f* enters and leaves the tank through such gaps; it is deflected by the walls of the gaps as shown in Figure 2 and thus serves to seal the gaps against the escape of solvent from the tank.

A roller *g* at the bottom of the tank around which the fabric passes guides the latter through the impregnating liquid which is maintained at

the correct level by an inlet valve *h* controlled by a float *i*.

Adjacent to the outlet gap is a pair of rods *j, k*, between which the fabric passes just prior to leaving the machine. Such rods which do not revolve, but deflect the tensioned fabric as shown in Figure 2 and serve to remove excess liquid from the fabric. The rod *k* is adjustable relatively to the rod *j* from outside the machine by the screw *m* to alter the extent to which the fabric is deflected and so the extent of the scraping action of the rods upon the fabric.

All the rods are located at their ends in slots in the tank walls and can be readily removed when the lid is out of position. The adjacent edges of the lid and tank flanges are rounded to prevent damage to the fabric passing between them. I provide a drain connection *n* for emptying the tank and I may provide a screw or jack *o* for tilting the tank to facilitate drainage. A gauge *p* can be used for showing the liquid level in the tank.

What I claim is:

25 A machine for use in impregnating fabrics with a volatile liquid or with a solution containing a volatile liquid comprising a tank or vessel of a length to suit the width of the fabric being impregnated, with at least one roller around which the fabric travels beneath the surface of the impregnating liquid in the tank or vessel, spaced rods adjacent to the fabric exit from the tank and above the level of the liquid therein, each rod deflecting the path of the cloth as it passes between and over the rods so that the latter remove 30 excess of liquid from the fabric, just prior to its leaving the tank or vessel, and a lid which makes a joint with the vessel except at the parts where the fabric passes into and out of the vessel, the lid at such parts coming adjacent to surfaces of the vessel, the adjacent surfaces of lid and vessel each deflecting the path of the fabric passing into and out of the vessel so that the fabric serves to seal the gap between the said parts and to prevent or minimize escape of solvent there, the said surfaces serving also as spreader blades on both 35 sides of the fabric which is under tension and thus insure a smooth even surface spreading.

RUDOLPH HERBERT CZEZWITZKA.
